INTERLOCK

George B. Thieme, Bloomfield, N. J., assignor to
 Eclipse Aviation Corporation, East Orange,
 N. J., a corporation of New Jersey

Application June 21, 1933, Serial No. 676,977
 Renewed April 23, 1935

21 Claims. (Cl. 70—130)

This invention relates to interlocks and more particularly to interlocks which are adapted to lock electrical switches or other devices operable by a plurality of revolutions of a rotary shaft.

In certain switch installations it is necessary to complete a number of revolutions of a hand operated shaft to move the switch from one position to another and an object of the present invention is to prevent locking of the switch until the necessary number of revolutions have been completed. The interlock is of the key actuated type wherein the keys are adapted to operate similar interlocks and the keys are not removable until moved to a locking position.

Another object of the invention is to provide an interlock with a plurality of aligning openings and solid members which cooperate to lock the device except in certain predetermined positions.

Another object of the invention is to provide an interlock which is adaptable to a rotary actuated operating shaft.

A feature of the invention relates to an interfering plate which is adapted to block the movement of the main locking bolts except in certain predetermined positions of the shaft. In the illustrative embodiment the interfering plate is actuated by a nut which moves the plate into and out of interfering relation with the locking bolts, the nut being threaded on the shaft and having a cam slot cooperative with the interfering plate to move it radially of the shaft.

Other objects and features of the invention will be apparent from the following description in connection with which a preferred embodiment of the invention has been shown in the accompanying drawing in which,

Fig. 1 is a side elevation of the device with cover removed and partly in section;

Fig. 2 is an elevation of the shafts and parts thereon, taken at right angle to that in Fig. 1;

Fig. 3 is a section through the interfering plate, taken along line 3—3 of Fig. 1;

Fig. 4 is similar to Fig. 3, except that the interfering plate is in a locking position; and

Fig. 5 is a modification of the nut shown in Fig. 2 for use when a neutral locking position is required.

Fig. 6 is a sectional view illustrating one method of preventing the removal of the key except in the locked position; Fig. 7 is a plan view of the lock shown in Fig. 6.

Referring to the drawing, the interlock which may be applied to either a horizontally or a vertically mounted disconnecting switch (not shown) consists of a casing 3 secured as by means of bolts

4 to a column 6. Journalled vertically through casing 3 is a shaft 7, the lower end of which (as viewed in Fig. 1) is coupled to a gear box 8 operable by hand crank 9 and the upper end of which is coupled to a switch operating pipe or sleeve 11. 5 Also connected to the shaft by a pin 12 is a lead screw 13 upon which moves a nut 14 (best shown in Fig. 2) each side of which is machined flat and equipped with a groove 16, comprising a straight central portion and an inclined portion at each 10 end thereof. Surrounding the nut is an interfering plate 17 having inwardly projecting tongues 18 registering with grooves 16 forming face cams for the guidance of the tongues. From the external side of the plate protrude ears 19, each of 15 which contains a slot 21 through which are inserted screws 22 and about which, by means of sleeves 23, the plate is supported, the interfering plate being radially slideable between the screw head and sleeve. The ears 19 further contain 20 square openings 24 so located that they admit the slideable interlock bolts 26 of the same shape, and are in alignment with the bolts only when tongues 18 are in the inclined end portions of the groove 16. When nut 14 is in an intermediate position the central portion of groove 16 moves plate 17 to the position shown in Fig. 4, wherein the plate openings 24 are out of alignment with bolts 26 causing bolts to be immovable. These bolts are parallel to, and equidistant from the shaft 7 and 30 are slidably mounted in wall 27 of the housing 3 in which the shaft is journalled, the lower portion of each bolt being connected through a pin and slot arrangement with a rotatable arm 28 whose movement is controlled by rotation of a key 25 35 which is inserted in the cylinder lock 25a, to which the arm is attached.

The locking of bolts 26 is accomplished through means of a notched wheel 29, secured to shaft 7 by a pin 32 and abutting a boss on the under 40 side of the wall 27 as viewed in Fig. 1. By undercutting the periphery of the wheel, two cylindrical disks, 33 and 34 respectively, are formed around the outside edge of the wheel which revolves upon operation of the shaft through 45 grooves 36 milled across the inner side of the bolts 26. Likewise, the disks have grooves or notches 37 milled across their periphery on opposite sides to permit the sliding of bolts 26 in certain positions of wheel 29.

It is preferred to use locks of the well known type in which the key is removable only in the locked position, therefore it is apparent that in the position of the parts as shown in full lines in Fig. 1, the keys are not removable but the handle 50 55

9 may be rotated to actuate the switch operating sleeve 11 or either of bolts 26 may be moved to the dotted line position. Many types of locks in which the keys are removable only in the locked position are sold commercially and no claim is made to any particular form of lock. The lock shown in Figs. 6 and 7 is illustrative of the type with which the interlock is to be used and it may be seen that the key 25 is not removable from lock 25a until the projection 31 on the key aligns with notch 30, and that this position of the key corresponds to the locked position of bolt 26 illustrated in broken lines in Fig. 1. It is understood that this interlock is intended for use with other similar interlocks operated by the same keys whenever they are released by a movement of the bolts 26 corresponding to the locked position of the locks 25a. The shaft 7 may be locked in the position shown in Fig. 1 by movement of either bolt 26 or may be locked in a position wherein nut 14 has moved to the dotted line position of Fig. 2, but cannot be locked in any intermediate position because of the action of interfering plate 17. If it were not for the interfering plate the shaft 7 could be locked after 180 degrees rotation if notches 37 are identical or after 360 degrees if they are of unequal shape or size, but by the use of the interfering plate locking is prevented until the nut 14 is in a position wherein the openings 24 are in alignment with the bolts and which may be any multiple of 180 or 360 degrees.

If it is desired to provide an interlock in which the switch may be locked in an intermediate position, the nut 14a shown in Fig. 5 may be used. In this form of the invention the groove 16a is provided with a V-shaped portion 38 wherein the tongues 18 will be guided to a position wherein the openings 24 are aligned with bolts 26.

In the operation of the device if it is desired to actuate another interlock of similar construction, one of keys 25 will be rotated to move bolt 26 to the dotted line position. Key 25 may then be removed for actuation of the second interlock, but the first interlock will prevent actuation of the switch because notches 36 and 37 will not be in alignment. If the second interlock is identical with the one shown, both keys will have to be removed for use in the second interlock, but it is understood that the second interlock may be operable by a single key in which case the second key is available for a third interlock. The keys are not removable until bolts 26 have been moved to locking position, therefore as the bolts can only be moved in certain positions of the interfering plate 11, the operator is assured that no other interlock can be operated without the switch being in a predetermined position.

While a preferred embodiment of the invention has been illustrated and described, it is understood that this showing and description are illustrative only and that the invention is not considered as limited to the form shown and described, or otherwise, except by the terms of the following claims.

What is claimed is:

1. In an interlock, a rotatable shaft, an axially movable bolt adjacent the shaft for locking the same, and a transversely movable member actuated by shaft rotation for locking the bolt.

2. In an interlock, a rotatable shaft, an axially movable bolt adjacent the shaft for locking the same, a movable member actuated by shaft rotation for locking the bolt, and said member having

an opening therein movable into and out of registration with the end of said bolt.

3. In an interlock, a rotatable shaft, an axially movable bolt adjacent the shaft for locking the same, and a transversely movable member actuated by shaft rotation, said member being adapted to move into locking relation with the bolt only after a plurality of shaft revolutions. 5

4. In an interlock, a rotatable shaft, an axially movable bolt adjacent the shaft for locking the same, a transversely movable member, said member being adapted to move into locking relation with the bolt only after a plurality of shaft revolutions, a nut threaded on the shaft having means thereon coacting with the radially movable member to actuate the same, and means preventing rotation of the nut. 15

5. In an interlock, a rotatable shaft having a collar thereon provided with a peripheral notch, a bolt parallel to the shaft and slidable in the notch, said bolt having a notch adapted to align with the collar in one position of the bolt, means for sliding the bolt, and means actuated by shaft rotation for preventing sliding movement of the bolt. 25

6. In an interlock, a rotatable shaft having a collar thereon provided with a peripheral notch, a bolt parallel to the shaft and slidable in the notch, said bolt having a notch adapted to align with the collar in one position of the bolt, means for sliding the bolt, and means actuated by shaft rotation for preventing sliding movement of the bolt, said means including a transversely movable member adapted to interfere with the end of the bolt. 35

7. In an interlock, a rotatable shaft having a collar thereon provided with a peripheral notch, a movable bolt parallel to the shaft and slidable in the notch, said bolt having a notch adapted to align with the collar in one position of the bolt, means for sliding the bolt, and means actuated by shaft rotation to engage the bolt for preventing sliding movement of the bolt. 40

8. In an interlock, a rotatable shaft having a collar thereon provided with a peripheral notch, a bolt parallel to the shaft and slidable in the notch, said bolt having a notch adapted to align with the collar in one position of the bolt, means for sliding the bolt, and means actuated by shaft rotation for preventing sliding movement of the bolt only after a plurality of shaft revolutions. 45

9. In an interlock, a rotatable shaft having a collar provided with a notch, a bolt having a notch slidably mounted in the collar notch for locking the shaft against rotation, said shaft having a threaded member thereon, an axially movable nut on said threaded member having a cam groove, a transversely movable member adapted to interfere with bolt movement and having means thereon cooperative with the groove to move the member, and means for preventing rotation of the member and the nut. 55

10. In an interlock, a rotatable shaft having a collar provided with a notch, a bolt having a notch slidably mounted in the collar notch for locking the shaft against rotation, said shaft having a threaded member thereon, an axially movable nut on said threaded member having a cam groove, a transversely movable member adapted to interfere with bolt movement and having means thereon cooperative with the groove to move the member, and means for preventing rotation of the member and the nut, said member being arranged to interfere with bolt movement only in the extreme positions of the nut. 65

11. In an interlock, a rotatable shaft having a collar provided with a notch, a bolt having a notch slidably mounted in the collar notch for locking the shaft against rotation, said shaft having a threaded member thereon, an axially movable nut on said threaded member having a cam groove, a transversely movable member adapted to interfere with bolt movement and having means thereon cooperative with the groove to move the member, means for preventing rotation of the member and the nut, and manually operable means for actuating said bolt.
12. In an interlock, a rotatable shaft, a slideable bolt for locking the shaft against rotation, a member slideable at right angles to the bolt, said member having an opening large enough to receive the bolt, and means actuated by shaft rotation for moving said opening into and out of alignment with said bolt.
13. In an interlock, a rotatable shaft, a slideable bolt for locking the shaft against rotation, a member slideable transversely of the bolt, said member having an opening large enough to receive the bolt, and a cam actuated by shaft rotation cooperating with the member to move the opening into and out of alignment with said bolt.
14. In an interlock, a rotatable shaft, an axially movable bolt adjacent the shaft for locking the same, means for moving the bolt, and a member transversely movable by shaft rotation into and out of locking relation with the ends of said bolt.
15. In an interlock, a rotatable shaft, a pair of axially movable bolts adjacent the shaft each of which is axially movable to lock the shaft, and a transversely movable member actuated by shaft rotation for simultaneously locking both of said bolts.
16. In an interlock, a rotatable shaft having a collar thereon provided with a pair of spaced peripheral notches, a pair of bolts parallel to the shaft and slideable in the notches respectively, each of said bolts having a notch therein adapted to align with the collar in one position of the bolt for permitting rotation of the collar therein, means for selectively moving each bolt, and means actuated by shaft rotation for simultaneously preventing sliding movement of both bolts only after a plurality of shaft revolutions.
17. In an interlock, a rotatable shaft, a movable bolt adjacent the shaft for locking the same, a member movable along said shaft by rotation thereof, and a second member movable into and out of locking relationship with said bolt, said second member being actuated by the first mentioned member.
18. In an interlock, a rotatable shaft having a threaded portion, a nut on said threaded portion, means preventing rotation of the nut, means preventing axial movement of the rotatable shaft, a bolt for locking said shaft, and means movable by said nut into and out of locking relationship with said bolt.
19. In an interlock, a rotatable shaft having a threaded portion, a nut on said threaded portion, means preventing rotation of the nut, means preventing axial movement of the rotatable shaft, a bolt for locking said shaft, and means movable by said nut into and out of locking relationship with said bolt, said means having two non-locking positions and a locking position intermediate said non-locking positions.
20. In an interlock, a rotatable shaft having a threaded portion, means preventing axial movement of the shaft, a nut on said threaded portion, means preventing rotation of said nut, a bolt for locking said shaft against rotation, and a locking member for said bolt, said member being movable by said nut and having spaced bolt receiving openings therein adapted to align with said bolt at corresponding positions of the nut and an intermediate portion preventing movement of said bolt to a locking position with said shaft.
21. In an interlock, a rotatable shaft having a threaded portion, means preventing axial movement of said shaft, a nut on said threaded portion, means preventing rotation of said nut, a collar having an opening secured to said shaft, a bolt movable into and out of engagement with the opening to lock the shaft, and a member movable by said nut into and out of locking engagement with said bolt, said member having two non-locking positions and an intermediate locking position.

GEORGE B. THIEME.
